UNITED STATES PATENT OFFICE.

WAYNE E. DUNSTON, OF DETROIT, MICHIGAN, ASSIGNOR TO THE C. G. SPRING & BUMPER COMPANY, OF DETROIT, MICHIGAN, A CORPORATION OF DELAWARE.

DESIGN FOR A CLAMP FOR AN AUTOMOBILE BUMPER.

Application filed February 2, 1925. Serial No. 12,242. Term of patent 14 years.

To all whom it may concern:

Be it known that I, WAYNE E. DUNSTON, a citizen of the United States, residing at Detroit, in the county of Wayne and State of Michigan, have invented a new, original, and ornamental Design for Clamps for Automobile Bumpers, of which the following is a specification, reference being had to the accompanying drawing, forming part hereof, wherein—

Fig. 1 represents a front elevation and Fig. 2 a side elevation of a clamp exhibiting my new design.

I claim:

The ornamental design for a clamp for an automobile bumper, as shown.

WAYNE E. DUNSTON.
